UNITED STATES PATENT OFFICE.

EVAN EVANS, OF KAYLOR, PENNSYLVANIA.

SHUT-OFF VALVE FOR OIL-WELLS.

SPECIFICATION forming part of Letters Patent No. 469,996, dated March 1, 1892.

Application filed September 17, 1891. Serial No. 405,979. (No model.)

To all whom it may concern:

Be it known that I, EVAN EVANS, of Kaylor, in the county of Armstrong and State of Pennsylvania, have invented certain new and 5 useful Improvements in Shut-Off Valves for Oil-Well; and I do hereby declare the following to be a full, clear, and exact description of the invention, such as will enable others skilled in the art to which it pertains to make 10 and use it, reference being had to the accompanying drawings, which form part of this specification.

My invention relates to an improvement in shut-off valves for oil-wells; and it consists in 15 the construction and arrangement of parts, which will be fully described hereinafter, and particularly referred to in the claims.

The object of my invention is to provide a 20 shut-off valve to be applied to the lower end of the working barrel of an oil-well for the purpose of preventing the oil from running back through the well to the rock when the working rods and valves are removed for the purpose of repair, or for the purpose of changing 25 the cup leather packing, which has to be done frequently.

In the drawings, Figure 1 is a side view of a shut-off valve which embodies my invention. Fig. 2 is a vertical section of the same, 30 taken through the center. Fig. 3 is a longitudinal sectional view, showing the relative position of the shut-off valve to the working barrel.

My cut-off valve consists of an upper hollow 35 perforated portion A, which has an upper perforated top or end B. Screwed or otherwise secured in the lower end of this casing A is a valve-seat C, which extends down below the casing A a suitable distance and 40 has its lower end screw-threaded, as shown. Screwed upon this screw-threaded lower end of the valve-seat C is a ring D, which has extending downward therefrom a yoke E, which is provided with a vertical opening F, through 45 which the valve-rod G passes and is guided. This yoke also acts as a support for the spiral spring H, which is placed around the valve-stem G, and has its upper end engaging the under side of the valve I and holds the valve 50 normally upward, as shown in Fig. 2.

Placed between the upper edge of the yoke-ring D and the lower edge of the casing A is

a suitable packing J, which makes a tight fit of the shut-off valve in the lower end of the working barrel. This packing is placed 55 tightly in the lower end of the barrel and supports the casing in position therein.

Where a shut-off valve is not used, when the working valves are removed for any purpose, which has to be done frequently, all of 60 the oil and water rush back upon the oil-rock, which is very damaging to the well, and it is this that I desire to prevent by the use of my valve. By placing my valve in the lower end of the working barrel and placing 65 a packing in the well between the water and oil-bearing strata, when the working valves are removed the pressure of the oil in the tubing closes the valve against the pressure of the spring and holds all of the oil in the tub- 70 ing until the working valves are placed in position again. Then as soon as the working valves are started, the pressure is removed from the shut-off valve and the spring forces it upward, allowing a free flow of oil through the 75 shut-off valve from the rock. Where a shut-off valve is not used and the working valves are removed for changing the cup leather packing, or for any other purpose, one or two days' 80 production is lost, owing to the fluid rushing back to the rock; but where my valve is used there is no loss of fluid, and when the working valves are replaced and started the oil begins to flow at once; also, by the use of this valve I do not have to use any standing valve, 85 but use a check-valve at the top of the working barrel. When the piston-rod is removed, all of the valves are removed with it, so that they can be examined, while my valve remains in place in the lower end of the working barrel 90 and prevents any backward flow of the fluid.

My shut-off valve has no operation or function as long as the working valves are in operation; but as soon as they are removed the pressure of the fluid in the well closes the 95 valve and prevents it from rushing back to the oil-rock.

By means of a valve of the above-described construction I produce a very cheap and simple means for preventing damage to oil-wells 100 and a loss of fluid by preventing it from flowing back to the rock. The lower end of the valve-stem is screw-threaded and extends through the yoke, as shown, and has applied

thereto a screw-nut M, by means of which the valve can be brought down upon the spring and thus the tension of the spring regulated, as will be readily understood.

5 Having thus described my invention, I claim—

1. A shut-off valve for oil-wells, consisting of a perforated casing having a valve-seat inside thereof at its lower end, a valve placed inside of the said casing above the said seat, a valve-stem and a yoke through which the valve-stem passes, and a spring which is placed between the yoke and the valve for holding it normally up out of contact with its seat, substantially as specified.

10 2. A shut-off valve for oil-wells, comprising a perforated casing, a valve-seat placed in its lower end having a screw-threaded lower end, a yoke placed upon the screw-threaded lower end of the said seat, a valve within the casing above the said seat, a valve-stem passing through the yoke, and a spring having one

end placed upon the yoke and its other end forcing the valve upward, substantially as specified.

15 3. In a shut-off valve for oil-wells, a perforated casing having a valve-seat placed in its lower end with an extended portion, a yoke placed upon the said extended portion having a vertical opening, a valve and a valve-rod, the valve-rod having its lower end passing through the vertical opening of said yoke and screw-threaded, a nut placed upon the screw-threaded lower end of the valve-rod, and a spring placed between the yoke and the valve, where- 30 by the tension of the spring can be regulated, all combined substantially as set forth.

35 In testimony whereof I affix my signature in presence of two witnesses.

EVAN EVANS.
